ENGINE PROTECTIVE SYSTEM

Charles N. Reavis, Raleigh, N. C., assignor of two-thirds to Silas B. Coley, Raleigh, N. C.; Charlotte L. Reavis administratrix of said Charles N. Reavis, deceased.

Application December 14, 1944, Serial No. 568,125

3 Claims. (Cl. 123—198)

1

This invention relates to an electric protective system for the engine of a motor vehicle, and the primary object of the invention is to provide means to automatically render the engine inoperative within a short time after the occurrence of a condition which is detrimental to the engine if the latter is allowed to continue to operate for an extended period of time.

More particularly, the present invention contemplates the provision of an efficient system of the above kind, by means of which the engine will be automatically rendered inoperative within a short time after the engine starts to overheat due to failure of the cooling system thereof, or within a short time after the lubricating system of the engine fails.

Another object of the invention is to provide a protective system of the above kind which may be readily produced and installed, and which is comparatively simple in construction and highly efficient in operation.

More specific objects and features of the invention will become apparent from the following description when considered in connection with the accompanying drawings, and the invention consists in the novel form, combination and arrangement of parts hereinafter more fully described, shown in the drawings and claimed.

In the drawings, wherein like reference characters indicate corresponding parts throughout the several views:

Figure 1 is a diagrammatic view illustrating the present invention as applied to an internal combustion engine having a dual ignition system including a pair of distributors.

Figure 2 is a view similar to Figure 1, illustrating the invention as employed in connection with Diesel engines.

Figure 3 is an enlarged sectional view showing details of the thermal device for releasably holding the contact actuator in inoperative position, and

Figure 4 is a fragmentary elevational view showing further details of the installation illustrated in Figure 2.

Referring in detail to the drawings, 5 indicates a casing communicating with the upper header of the radiator of an engine cooling system. Pivoted at 6 within this casing is a rod 7 having a float 8 on one end thereof which is subjected to the level of the water within the casing 5. The other end of rod 7 carries a contact 9 which is movable into or out of engagement with a further contact 10 that is fixed to and insulated from the casing 5. The contact 10 is located above the

contact 9, and a flexible contact 11 is disposed at the opposite side of the contact 9 and carried by a support 12 rigid with and in electrical connection with the casing 5. The contact 11 is normally tensioned to engage a second fixed contact 13 carried by and insulated from the casing 5, and it is noted that the casing 5 is grounded, as at 14. The arrangement is such that when the level of the water in the casing 5 becomes unduly low, as when the engine becomes overheated, the rod 7 will have swung in a direction to engage the contact 9 with the contact 10 for a purpose to be later described. The arrangement is also such that when the water rises to the proper level within the casing 5, the contact 9 will engage contact 11 and flex the same so as to disengage it from the contact 13.

The system further includes an oil-pressure switch including a diaphragm 15 mounted in a casing 16 and having a pin 17 that projects upwardly through the top of said casing 16. The casing 16 has an inlet nipple 18 by means of which the casing 16 is placed in communication with the engine lubricating system so as to subject the under side of the diaphragm 15 to the pressure within said system.

Carried by the casing 16 is a shell 19 within which a multiple contact of bell crank form, is pivoted, as at 20. One arm 21 of the multiple contact is arranged to engage a fixed contact 22 carried by and insulated from the casing 16. The other arm 22' of the multiple contact extends between and is arranged to alternately engage the spaced fixed contacts 23 and 24 mounted at opposite sides thereof. These contacts 23 and 24 are carried by the shell 19 and insulated from the latter. Movement of diaphragm 15 and the multiple contact 21, 22' is yieldingly resisted by a helical compression spring 24' whose strength may be adjusted by means of an adjusting screw 25. The spring 24' is arranged so that it acts in opposition to the pressure of the oil against the diaphragm 15, and such pressure of the oil actuates the multiple contact 21, 22' in a direction to disengage contact 21 from contact 22 and contact 22' from contact 23 and into engagement with contact 24. The arrangement is such that when the pressure in the lubricating system of the engine is below proper operating pressure, the contact 21 will engage the contact 22 and the contact 22' will engage the contact 23. On the other hand, when the pressure in the lubricating system is sufficiently high for proper operating conditions, diaphragm 15 will be flexed so as to disengage the contact 21 from the contact 22 and to

simultaneously disengage contact 22' from contact 23 and engage said contact 22' with contact 24.

The output terminal 26 of a generator 27, driven by the engine, is connected by a wire 28 with the contact 23. One terminal of a storage battery 29 is connected by a wire 30 with the contact 24. The generator 27 is grounded, as at 31, while the other terminal of battery 29 is grounded, as at 32. Also, shell 19 and casing 16 are grounded, as at 33. A wire 34 connects contact 10 with contact 22, and contacts 21 and 22' are insulated from each other.

The system further includes a time-delay switch that embodies three parallel and adjacent flexible contacts 35, 36 and 37, which are insulated from each other but which are arranged so that they can be flexed to engage each other at their free ends. This switch also includes a fixed contact 38 normally engaged by a flexible contact 39, and a lamp socket 40 is provided into engagement with which the contact 39 may move when disengaged from contact 38. A sliding contact actuator 41 is suitably mounted adjacent the free ends of the contacts 35, 36 and 37, and is yieldingly urged toward the latter by means of a helical tension spring 42. The arrangement is such that when the spring 42 moves the actuator 41 in one direction, said actuator engages the contact 35 and flexes it into engagement with the contact 36, and then flexes contact 36 into engagement with contact 37. The contacts 35, 36 and 37 are normally separated, and the actuator 41 is releasably held in retracted position against the action of spring 42 by means of a thermal device, generally indicated at 43 and detailed in Figure 3. As shown in the latter figure, this thermal device includes a stationary hollow threaded stud 44 on which is rotatably fitted a sleeve 44a that is provided with teeth 45. The sleeve 44a is prevented from rotating relative to stud 44 by means of fusible solder or the like placed between the stud and the sleeve, as at 46. Disposed within the stud 44 is a heating element 47, one terminal of which is connected by a wire 48 with contact 38. The other terminal of heating element 47 is connected by wire 49 with wire 34'. The other terminal of heating element 47 is connected by a wire 49 with the wire 34 at a point intermediate the contacts 10 and 22. The actuator 41 includes a part 50 arranged to engage the free end of contact 39 so as to disengage the latter from the contact 38 when said actuator is moved by the spring 42 to cause engagement of the contacts 35, 36 and 37 with each other.

Contact 36 is grounded at 51, and contact 22' is connected by a wire 52 with one terminal of each of a pair of lamp sockets 53 and 53a and with one side of a resistor 54. The other side of resistor 54 is connected by a wire 55 with the contact 39, while the other side of a lamp socket 53 is connected by a wire 56 with the contact 13. The other side of lamp socket 53a is connected by a wire 57 to one terminal of a test switch 58 whose other terminal is grounded, as at 59. Contact 35 is connected by a wire 60 with the feed terminal of one distributor 61 of the dual ignition system of the engine, said wire 60 having a fuse 62 therein. Contact 37 is connected by a wire 63 with the feed terminal of a second distributor 64 of the dual ignition system of the engine, and said wire 63 has a fuse 62a therein. In practice, suitable signal lamps will of course be placed in the sockets 40, 53 and 53a. The actuator 41 has a lug at 65 that engages with gear

45 of the thermal device 43 so as to normally hold said actuator 41 in retracted position.

Assuming that the engine is operating at a speed to drive the vehicle at a speed of more than 5 15 to 18 miles an hour, and that the level of the water in the casing 5 should unduly lower so as to result in overheating of the engine, the contact 9 will engage contact 10 so as to ground the latter through the ground 14. At this time, 10 current will flow from wire 52 through resistor 54, wire 55, contact 39, contact 38, wire 48, heating coil 47, and wire 49, to contact 10. Thus, 15 the circuit of the heating coil 47 is closed so that the fusible element or solder 46 will be melted within a predetermined time for freeing the parts 15 44a and 45, thereby allowing spring 42 to move actuator 41 to the right of Figure 1. This causes contact 39 to be disengaged from contact 38 so as to break the circuit of the coil 47 and to cause the lamp in the socket 40 to be lighted. 20 At the same time, the feed terminals of distributors 61 and 64 will be grounded so as to render the engine inoperative. The current flows from the feed terminal of distributor 61 through wire 68, contact 35, and contact 36, to ground 51. 25 From the feed terminal of distributor 64, the current flows through wire 63, contact 37, and contact 36, to ground 51. It will be noted that when the low water condition causes grounding of contact 10, the circuit of the lamp in socket 53 will be closed to warn the driver that the engine will be stopped within a short time. In lighting the lamp of socket 53, the current flows by way of wire 52, through socket 53, wire 56, contact 13, 30 and contact 11, to ground 14. When the level of the water lowers further so that contact 9 engages contact 10, the circuit of the lamp in socket 53a is closed so as to indicate that the danger has increased to the point where the system will shortly render the engine inoperative. At this time, the current flows from wire 52 through socket 53a, wire 57, wire 49, wire 34, contact 10, 35 and contact 9, to ground 14. When the water in the casing 5 is at the proper high level, contact 9 will be disengaged from contact 10 and will hold contact 11 out of engagement with contact 13, thereby breaking the circuit of heating element 47 and that of the lamp in socket 53. If the engine is idling, the current will be derived from generator 27 because the oil pressure will be insufficient to disengage contact 21 from contact 22 and contact 22' from contact 23. At this time, the current flows from generator 27 through wire 28, contact 23, and contact 22', to the main feed wire 52. However, when the engine operates at a higher speed and the oil pressure is increased, the contact 21 will be disengaged from contact 22 and contact 22' will disengage from contact 23 and engage contact 24, 40 thereby causing the current to be derived from the battery 29 by flowing through wire 30, contact 24, and contact 22', to wire 52.

After operation of the system, the actuator 41 may be reset in retracted position by means of a reset button 66. This reset button is arranged to engage the contact 37 and is movable toward the actuator 41 so as to shift the latter to retracted position by forcing the contacts 35, 36 and 37 against said actuator 41 and moving the latter against the tension of spring 42. The actuator 41 will be retained in this retracted position when reset, if the reset button 66 is operated after the solder has cooled and hardened again. The solder is provided between the stud and sleeve, and the latter is held on the stud by disc d.

The system operates substantially the same as described above in case the pressure of oil in the lubricating system unduly lowers. When the latter occurs, the contact 21 will be engaged with contact 22 so that the wire 34 is connected with the ground 33 through contact 22, contact 21, and casing 16. If the generator is then operating at a higher than engine idling speed, the current derived from said generator will be sufficient to energize heating element 47 so that it will melt the fusible element 46 of the thermal device 43, but it is to be understood that the current derived from generator 27 when operating at lower speeds will be insufficient to energize heating element 47 to the extent that it will melt the fusible element 46. Assuming that the oil pressure in the lubricating system has unduly lowered, as mentioned above, the current will flow from generator 27 through wire 28, contact 23, contact 22', wire 52, resistor 54, wire 55, contact 39, contact 38, wire 48, heating element 47, wire 49, wire 34, contact 22, contact 21, and casing 16, to ground 33, thereby closing the circuit of the heating element 47. At the same time, current will flow from wire 52 through socket 53a, wire 57, wire 49, wire 34, contact 22, contact 21, and casing 16, to ground 33. This will cause lighting of the lamp in socket 53a so as to warn the driver that the system has been rendered operative and that the engine will be stopped within a short period of time or as soon as the fusible element is melted. This occurs in the same manner as previously described and when the actuator 41 is released and actuated by the spring 42, the distributors 61 and 64 will be grounded in the same way.

As shown in Figure 2, the installation for Diesel engines is the same as that for internal combustion engines employing distributors, except that wire 52 is connected with wire 63 by a jumper wire 63 instead of being connected to the distributor 64, and the wire 60 is connected with the feed terminal of an emergency stop solenoid 69 instead of being connected to the distributor 61. The other terminal of solenoid 69 is grounded at 70, and such solenoid is part of standard equipment on vehicles powered by Diesel engines, such equipment acting, when the solenoid is energized, to cause stopping of the engine. This equipment usually includes a lever 71 (see Fig. 4), for actuating a clutch 72 between the engine blower or air compressor 73 and its operating motor 74, the solenoid 69 acting to engage the lever 71 so as to hold it in the position wherein the clutch 72 is engaged. The arrangement is such that when the solenoid 69 is energized, the lever 71 is released and moves by gravity or through the action of a spring 75 to disengage clutch 72 and thereby disconnect the motor 74 from the blower or compressor 73. When the blower or compressor 73 is thus thrown out of operation, supply of air under pressure to the engine is discontinued so that the latter is rendered inoperative. In this embodiment, the contact 36 is disconnected from the ground, or is not grounded, as at 51 in Figure 1. The current will flow, after actuator 41 has caused engagement of contacts 35, 36 and 37, from wire 52 through wire 68, wire 63, contacts 37, 36 and 35, and wire 60, to solenoid 69. This causes the solenoid 69 to be energized so as to release the lever 71 and permit the latter to throw the blower or compressor 73 out of operation to stop the engine as explained above. Otherwise, the system of Figure 2 is the same as that shown and described in connection

with Figure 1, and remaining parts of Figure 2 are indicated by the same reference characters as the corresponding parts of Figure 1. It is accordingly thought that the circuits can be readily traced in Figure 2 in view of the description thereof in connection with Figure 1, and without further explanation thereof herein. In both cases, an undesirable operating condition of the engine first causes the lighting of a warning light so that the driver is apprised of the fact that the engine will be rendered inoperative within a short time by reason of such operating condition. This will be followed within a short time by stopping of the engine automatically through the operation of the time-delay switch embodying actuator 41, heating coil or element 47, etc. The engine is not immediately thrown out of operation, and the operator is thus given an opportunity to move out of danger before the engine is stopped. For instance, should the undesirable condition occur when the vehicle is crossing railroad tracks, the engine will continue to run for a sufficient time to enable the operator to drive the vehicle off of the tracks. On the other hand, should the vehicle be approaching an intersection or railroad crossing, the operator can immediately throw the engine out of operation in the ordinary way before reaching the intersection or railroad crossing. He is warned of the need for the latter action because a warning signal is lighted before the system operates to render the engine inoperative.

From the foregoing description, it is believed that the construction and operation, as well as the advantages of the present invention, will be readily understood and appreciated by those skilled in the art. Minor changes in details of construction illustrated and described may be resorted to, such as fairly fall within the spirit and scope of the invention as claimed. It will be noted that the driver cannot hold the reset button in inwardly pressed position and continue to operate the engine because that action grounds the distributors from contacts 35 and 37 through contact 36, or causes current to flow to solenoid 69 via wire 63, contacts 37, 36 and 35 and wire 60.

What I claim is:

1. The combination with the pressure lubricating system of an internal combustion engine and a device whose operation is vital to the operation of the engine and which includes a circuit adapted to be closed to render the device inoperative and thereby stop the engine, of electrical means for rendering said device inoperative so as to stop the engine, said means embodying a spring-closed time-delay switch controlling said circuit and including a fusible element retaining the time-delay switch in open position and a heating element for melting said fusible element and permitting the time-delay switch to close said circuit, switch means operable by said time-delay switch to render the heating element inoperative when said circuit is closed, and an oil pressure switch subjected to the pressure of said lubricating system and operable upon a predetermined drop in the oil pressure to render said heating element operative when the time-delay switch is open.

2. The combination with the cooling and pressure lubricating systems of an internal combustion engine and a device whose operation is vital to the operation of the engine and which includes a circuit adapted to be closed to render the device inoperative and thereby stop the engine, of electrical means for rendering said device inoper-

ative so as to stop the engine, said means embodying a spring-closed time-delay switch controlling said circuit and including a fusible element retaining the time-delay switch in open position and a heating element for melting said fusible element and permitting the time-delay switch to close said circuit, switch means operable by said time-delay switch to render the heating element inoperative when said circuit is closed, a generator, a battery, an oil pressure switch subjected to the pressure of said lubricating system and operable upon a predetermined drop in the oil pressure to render said heating element operative when the time-delay switch is open and to connect said generator to one side of the heating element, said oil pressure switch further being operable by a predetermined rise in the oil pressure to render said heating element inoperative and to disconnect the generator from and connect one side of the battery to said one side of said heating element when the time-delay switch is open, a warning signal, and a float switch in the radiator of the cooling system operable upon a predetermined drop in the radiator water level to render said heating element and said signal operative when the time-delay switch is open and to render said heating element and said signal inoperative upon a predetermined rise in such water level.

3. The combination with the cooling system of an internal combustion engine and a device whose operation is vital to the operation of the engine and which includes a circuit adapted to be closed to render the device inoperative and thereby stop

10

15

20

25
